TOGGLE SWITCH

Albert E. Sparr, Meadville, Pa., assignor to Talon, Inc., a corporation of Pennsylvania

Application April 11, 1955, Serial No. 500,424

7 Claims. (Cl. 200—57)

The invention relates to electric switches and, more particularly, to a toggle switch of the so-called "subminiature" type.

Various types of electric snap switches have been heretofore suggested and used which usually employ a tiltable contact member. In some switches of this type the actuating means or tiltable contact member with which it co-operates oftentimes encountered a dead center position which was objectionable and interfered with the use and dependable operation of the switch. It is to a means for eliminating this dead center position of the switch that the present invention relates.

Accordingly, it is the general object of the present invention to provide an improved toggle switch having means incorporated therewith for eliminating any danger of the switch assuming a dead center position thereby providing a switch which is fool proof at all times.

It is another object of the invention to provide an improved toggle switch which is so constructed and arranged that a snap action will result when the actuating means of the switch is moved to open or close the circuit and which will insure a good electrical contact when in closed position thereby preventing destructive arcing between the contact members.

It is a more specific object of this invention to provide a new and novel means incorporated with the actuating means of the switch which acts as a fulcrum to aid in urging the tiltable contact member to its open and closed position so as to provide a more effective and efficient switch.

Various other objects and advantages of this invention will be more apparent in the course of the following specification, and will be particularly pointed out in the appended claims.

In the accompanying drawings, there is shown for the purpose of illustration, one embodiment and several modifications thereof, which my invention may assume in practice.

In these drawings:

Fig. 1 is a perspective view of a toggle switch with which my invention is incorporated;

Fig. 2 is a sectional view taken on line 2—2 of Fig. 1,

Fig. 3 is a sectional view taken on line 3—3 of Fig. 2,

Fig. 4 is a perspective view of the floating pin-like member constructed in accordance with the preferred form of my invention,

Fig. 5 is a similar view of the floating pin-like member showing a modification thereof, and

Fig. 6 is a sectional view similar to Fig. 2 showing a floating pin-like member of another modification in accordance with my invention.

The present invention is shown incorporated with a toggle switch of the type disclosed in corresponding applications Ser. No. 401,018, filed December 29, 1953, and Ser. No. 440,912, filed July 2, 1954. Such a switch as disclosed therein consists generally of a rectangular-shaped casing 2, preferably made of brass, but which may be made of any suitable moldable material which

2

houses the movable parts of the switch and which is open at both sides. The inner end of the casing 2 is closed by a base member 3 which is made of any suitable insulating material, such as melmac. The casing 2 may 5 be enlarged at its inner end to form a continuous internal shoulder 4 therearound for positioning and holding the base member 3 therein. This enlarged end of the casing has an ear portion 12 arranged therearound, which is clinched over and around the edge of the base 3, to hold 10 these two members securely together. In the base member 3, there is arranged two contacts 5 and 6 with one arranged at each end thereof. These contacts are merely rivet-heads having a convex surface and constituting a part of the rivets 7 and 8, respectively, which extend 15 through the base member 3. On the outer ends of these rivets 7 and 8 below the base 3, there is arranged a pair of identical wire terminal members 9 and 10 which are held in place by the heads of the respective rivets 7 and 8.

20 Centrally of the base member 3, there is arranged on the inner side thereof within the casing 2, a pivot or fulcrum member 13 which is secured to the base by means of a rivet 14 extending therethrough. On the upper side of the base 3 there is secured to the rivet 14, 25 a wire terminal member 15 identical with the wire terminal members 9 and 10. This pivot member 13 has a pair of spaced apart inwardly extending flange portions 16 in each of which there is arranged a substantially V-shaped bearing notch 17 for a purpose hereinafter to be described.

30 Within the casing 2, there is arranged a movable or tiltable contact member 18 preferably made from a highly conductive material. There is carried by this contact member 18 centrally thereof, a pair of spaced apart substantially V-shaped ear portions or projections 20 which are spaced apart substantially the same distance as the flange portions 16 of the pivot member 13 are spaced apart. These V-shaped notches 17 of the pivot member 13 are slightly larger than the notches 17 and are provided for a purpose hereinafter to be described. There is arranged on the pivot member 13 in the space between the inwardly extending flange portions 16 and between the inner ends of V-shaped bearing portions 20 of the contact member 18, a keeper member 36 having spaced 40 apart flange portions 37 for maintaining the V-shaped ears in position in the V-shaped notches so as to prevent transverse displacement thereof. This keeper member 36 is also held in position by the rivet 14 which is disposed in a hole in the bottom thereof. At each end of the contact member 18, there is arranged a contact button 21 made of a highly conductive material, such as silver, which engage and disengage with the respective contacts 5 and 6 arranged in the base 3.

45 On the outer side of the casing 2, there is arranged an exteriorly-threaded nipple-like member 22, the inner end of which is positioned in a circular hole in the outer side of the casing and which is held therein so as to be secured to the casing by means of an annular flange portion 23. There is arranged within the nipple-like member 22, a lever or handle member 24 having a portion 50 which extends out through a slotted opening 24a in the outer end of this nipple-like member 22. On the inner end of the lever 24, there is arranged a spherical or bulbous portion 25 which is disposed within the nipple-like member and bears against and is seated in an arcuate bearing surface 26 within the reduced neck portion at the outer end of the nipple-like member.

55 In one form of switch in connection with the use of my invention, as shown in Figs. 1 through 5 of the drawings, the lever or handle member 24 is axially hollow so as to provide a bore therein and there is arranged therein a compression spring 28 and a cylindrical plunger 29 with

the plunger having an arcuate or semi-spherical end portion 30. Within the nipple-like member 22 at the inner end thereof in one embodiment of my invention, there is arranged a floating pin-like member 31 which extends into the casing 2. One end of this pin-like member 31 has a concavity 32 therein so as to receive and co-operate with the inner arcuate or semi-spherical end portion 30 of the plunger 29. The other or inner end of this pin-like member 31 is arcuate or semi-spherical in shape, as at 33, and seats in a concavity 34 in a disc or button-like member 35 made of an insulating material and which is attached to contact member 18 centrally thereof, as at 27. There is arranged circumferentially around this pin-like member 31 intermediate the length thereof, an enlarged portion in the form of a disk-like or collar portion 40 which is disposed within the lower end of the nipple-like member 22 and which is adapted to co-operate with the inner side walls of this nipple-like member 22 in a manner and for a purpose hereinafter to be described.

In the modification shown in Fig. 5, there is arranged around the pin-like member 31, an annular member 41 having a plurality of outwardly flared resilient finger-like members 42 arranged therearound which are adapted to contact the inner wall of the nipple-like member 22.

In Fig. 6 of the drawing, there is shown another modification of my invention. In this construction, in place of a solid floating pin-like member, there is provided a compression coil spring member 43 having a ball-like portion 44 on one end thereof which is seated in a concavity 45 arranged in the inner end of the operating lever 46. On the opposite end of this spring 43 there is arranged a similar ball-like portion 47 which is seated in a concavity 48 arranged in the member 35 carried by the tiltable contact member 18. Intermediate the length of this spring member 43, there is arranged an enlarged convolution 50 which is adapted to bear against the inner wall of the nipple-like member 22 as in the other modifications.

As a result of my invention, it will be seen that there is provided an improved switch having means arranged therewith which will insure a positive action of the tiltable member at all times and eliminating any danger of the actuating means assuming a dead center position. This means also provides a snap action to the switch so as to eliminate drag and arcing which might result between the contact members.

While I have shown and described several embodiments which my invention may assume in practice, it will be understood that these embodiments are merely for the purpose of illustration and description, and that other forms may be devised within the scope of my invention as defined in the appended claims.

What I claim as my invention is:

1. In a switch of the class described, a housing, a base attached to said housing having at least a pair of fixed contacts with one arranged at either end thereof, a tiltable contact member arranged in said housing opposite said contacts and having contact means arranged at each end thereof adapted to engage alternately with the respective fixed contacts, current carrying means arranged on said base pivotally supporting said tiltable contact member centrally thereof, a manipulating lever arranged in said housing for actuating said tiltable contact member, a floating member arranged between the inner end of said manipulating member with one end of said floating member engaging the inner end of said manipulating member and the other end engaging said tiltable contact member centrally thereof, said floating member having an enlarged portion arranged intermediate its length and circumferentially therearound so as to provide a point of contact for said floating member with the inner wall of said housing and which acts as a fulcrum for said floating member whereby a snapping action is effected when the manipulating lever of the switch is actuated.

2. In a switch of the class described, the combination

as defined in claim 1, wherein the floating member arranged between the inner end of the manipulating lever and the center of the tiltable contact member consists of a floating pin-like member having an enlarged flange-like portion carried thereby intermediate its length and arranged circumferentially therearound.

3. In a switch of the class described, the combination as defined in claim 1, wherein the floating member arranged between the inner end of the manipulating lever and the center of the tiltable contact member consists of a floating pin-like member having an annular member arranged therearound intermediate its length, said annular member having a plurality of outwardly flared finger-like members so as to provide an enlarged portion arranged circumferentially around said floating pin-like member.

4. In a switch of the class described, the combination as defined in claim 1, wherein the floating member arranged between the inner end of the manipulating lever and the center of the tiltable contact member consists of a floating compression coil spring-like member having at least one enlarged convolution arranged intermediate its length so as to provide an enlarged portion arranged circumferentially therearound.

5. In a switch of the class described, a casing, a base attached to said casing having at least a pair of fixed contacts with one arranged at opposite ends thereof, a tiltable contact member arranged in said casing having contact means arranged at each end thereof adapted to engage alternately with the respective fixed contacts, current carrying fulcrum means carried by said base pivotally supporting said contact member centrally thereof, actuating means for tilting said contact member including a manually operated lever having a plunger slidably arranged in a bore therein axially thereof, a spring arranged in said bore for urging said plunger outwardly, and a floating pin-like member arranged within said casing, one end of said pin-like member engaging the outer end of said plunger and the opposite end of said pin-like member engaging said tiltable contact member and said operating lever arranged on said casing, said pin-like member having an enlarged flange-like portion carried thereby and arranged intermediate the length thereof, said enlarged portion adapted to contact the inner side wall of said housing which acts as a fulcrum for said pin-like member whereby a snapping action is effected when the operating lever of the switch is actuated.

6. In a switch of the class described, a casing, a base attached to said casing having at least a pair of fixed contacts with one arranged at opposite ends thereof, a tiltable contact member arranged in said casing having contact means arranged at each end thereof adapted to engage alternately with the respective fixed contacts, current carrying fulcrum means carried by said base pivotally supporting said contact member centrally thereof, actuating means for tilting said contact member including a manually operated lever having a plunger slidably arranged in a bore therein axially thereof, a spring arranged in said bore for urging said plunger outwardly, and a floating pin-like member arranged within said casing, one end of said pin-like member engaging the outer end of said plunger and the opposite end of said pin-like member engaging said tiltable contact member centrally thereof, and a housing for said pin-like member and said operating lever arranged on said casing, means arranged circumferentially around said pin-like member intermediate the length thereof so as to provide an enlarged portion which is adapted to contact the inner wall of said housing and which acts as a fulcrum for said pin-like member whereby a snapping action is effected when the operating lever of the switch is actuated.

7. In a switch of the class described, a casing, a base attached to said casing having at least a pair of fixed contacts with one arranged at opposite ends thereof, a tiltable contact member arranged in said casing having

contact means arranged at each end thereof adapted to engage alternately with the respective fixed contacts, current carrying fulcrum means carried by said base pivotally supporting said contact member centrally thereof, actuating means for tilting said contact member including a manually operated lever having a plunger slidably arranged in a bore therein axially thereof, a spring arranged in said bore for urging said plunger outwardly, a bulbous bearing portion arranged on the inner end of said lever, a cylindrical housing arranged on said casing for housing said bulbous bearing portion having an arcuate bearing surface carried thereby adjacent the outer end thereof in which said bulbous bearing portion is seated, a floating pin-like member arranged in the inner end of said housing and extending into said casing, one end of said pin-like member engaging the outer end of said plunger and the opposite end thereof engaging said tiltable contact member centrally thereof, convex-concave bearing surfaces arranged on the respective ends of said pin-like member, the plunger and the tiltable contact

member, so that the pin-like member will move freely between the plunger and the tiltable contact member when the lever is actuated, and an enlarged portion arranged circumferentially around said pin-like member intermediate the length thereof which is adapted to contact the inner wall of said housing and which acts as a fulcrum for said pin-like member whereby a snapping action is effected when the operating lever of the switch is actuated.
